(57) **CLAIM**

The ornamental design for a asymmetrical furniture pull, as shown and described.

DESCRIPTION

FIG. 1 is a front, left side perspective view of a first embodiment of the asymmetrical furniture pull of my design, shown on an article of furniture.

FIG. 2 illustrates a top plan view thereof.

FIG. 3 illustrates a front elevation view thereof.

FIG. 4 illustrates a left side view thereof.

FIG. 5 illustrates a right side elevation view thereof.

FIG. 6 is a front, left side perspective view of a second embodiment of the asymmetrical furniture pull of my design, shown on an article of furniture.

FIG. 7 shows a top plan view of the door of FIG. 6.

FIG. 8 shows a front elevation view of FIG. 6.

FIG. 9 illustrates a left side elevation view of the door of FIG. 6 showing my design; and,

FIG. 10 shows a bottom plan view of the door of FIG. 6. The broken lines shown are for illustrative purposes only and form no part of the claimed design.
